A. A. SCHWARTZ AND W. A. WHITESIDE,
COUPLING FOR ELECTRIC LIGHT FIXTURES.

APPLICATION FILED FEB. 1, 1918.

1,318,807.

Patented Oct. 14, 1919.

UNITED STATES PATENT OFFICE.

ARTHUR A. SCHWARTZ AND WILLIAM A. WHITESIDE, OF BUFFALO, NEW YORK,
ASSIGNORS TO J. ALFRED GAUTHIER, OF BUFFALO, NEW YORK.

COUPLING FOR ELECTRIC-LIGHT FIXTURES.

1,318,807.

Specification of Letters Patent. Patented Oct. 14, 1919.

Application filed February 1, 1918. Serial No. 214,989.

To all whom it may concern:

Be it known that we, ARTHUR A. SCHWARTZ, a citizen of the United States, and WILLIAM A. WHITESIDE, a subject of the 5 King of England, residing at Buffalo, in the county of Erie and State of New York, have invented new and useful Improvements in Couplings for Electric-Light Fixtures, of which the following is a specification.

This invention relates to the class of brackets or couplings employed for attaching electric light fixtures to walls or ceilings.

One of its objects is the provision of a 15 simple, compact and inexpensive coupling or fitting of this character which facilitates the connection of the fixture-wires to the supply wires of the building.

A further object is to provide the coupling with simple and reliable insulating means to prevent grounding or short-circuiting and protect the user from shocks.

In the accompanying drawings:

Figure 1 is a sectional elevation of a ceiling-fixture provided with the improved coupling. Fig. 2 is a transverse section on line 2--2, Fig. 1. Fig. 3 is a perspective view of the base-member. Fig. 4 is a similar view of the removable block and the tubular member carried by it.

Similar characters of reference indicate corresponding parts throughout the several views.

In the drawings, our invention is shown 35 in connection with a so-called hickey or coupling for converting a gas fixture into an electric fixture, but the improvement is equally applicable to other fittings or couplings.

1 indicates the ceiling and 1^a a gas-pipe from which the gas fixture has been removed and to which an electric lamp or fixture 2 is attached by means of our improved coupling. In the embodiment shown in the 45 drawings, this coupling comprises a hickey or base-member 3 having at its upper end a screw connection 4 which receives the projecting end of the externally-threaded gas pipe 1^a. At its lower end the hickey has a 50 three-sided socket preferably open at its front end and closed at its rear end, as shown at 5, while at the lower edges of its side-walls are inwardly-extending rails or

flanges 6 which converge toward the closed rear end of the socket.

Removably seated in said socket is a block 7 which carries the electric fixture. This block is wedge shaped or tapered to fit said socket and provided in its lateral edges with longitudinal grooves 8 which receive said 60 rails, thereby holding the block against vertical displacement in the socket. The block may be tightened and held in place by any suitable means. A screw 9 passing through the closed rear end of the socket into a 65 screw threaded hole 10 of the block, is shown in the drawings for this purpose. Upon tightening this screw, the block is firmly wedged into the tapering socket, holding the electric fixture rigidly in place.

Seated in a central or axial opening of the removable block is a metallic member 11 which is preferably tubular in the form of a sleeve, as shown. This member is provided at its lower end with an internally-threaded enlargement or connection 12 which receives the customary stem 13 of the lighting fixture. As shown at 14, the exterior of the connection 12 is of hexagonal or other flat-sided form to receive a wrench.

15 and 16 indicate tubular insulators or bushings of appropriate insulating material interposed between the sleeve 11 and the surrounding block 7 and provided with flanges 17, 18, respectively. The flange 17 85 is confined between the lower side of the block and the shoulder 19 of said sleeve, while the flange 18 bears against the upper side of the block. Interposed between the last-mentioned flange and the upset or 90 flanged upper end 20 of the sleeve is a metallic washer 21.

The usual conductors 22 of the lamp pass through its stem 13 and the sleeve 11 and are soldered or otherwise connected to the supply conductors 23, the solder joints being located outside of the coupling, as shown in Fig. 1.

Inclosing the fixture-stem is the customary finishing tube 24, while the coupling 100 and the solder-joints are concealed by the usual canopy 25. These housing-members form no part of the invention and may be of any desired form or design.

In assembling the parts and attaching the 105 fixture, the hickey is screwed upon the gas-

pipe 1^a and the fixture stem 13 is screwed into the block 7, the canopy 25 being slid back on the housing tube 24, as usual. The adjacent ends of the fixture and supply wires are then brought through the space between the upset upper end of the sleeve 11 and the opposing wall of the hickey and are soldered together, after which the block with the attached fixture is slid into its socket and clamped therein by the screw 9. Finally, the canopy is returned into place.

This construction permits the wires to be conveniently soldered together before introducing the block into its socket. Its compactness also permits the use of a comparatively shallow canopy and a correspondingly short fixture-stem, as shown in the drawings.

At the same time, the insulating bushings 15, 16 of the coupling obviate grounding or short-circuiting and protect the user.

We claim as our invention:

1. A coupling for electric fixtures, comprising a base-member having a laterally-opening socket, a block slideable laterally into said socket and having an opening, a supporting member arranged in said opening and adapted to carry the fixture, and tubular insulating bushings interposed between said supporting member and the wall of said block-opening and having retaining

flanges arranged on opposite sides of said block.

2. A coupling for electric fixtures, comprising a base-member, a block removably seated therein and having an opening, a supporting member arranged in said opening and provided at its upper end with a projecting flange and at its lower end with an enlarged screw connection forming a shoulder and adapted to receive the fixture stem, and tubular insulating bushings interposed between said supporting member and the wall of said block-opening, one of said bushings having a flange arranged between said block and the flange of said supporting member and the other bushing having a flange arranged between the block and the shoulder of the supporting member.

3. A coupling for electric fixtures, comprising a base-member having converging rails forming a tapering socket between them, a correspondingly-tapered block provided in opposite edges with grooves engaging said rails, a supporting member passing axially through said block and adapted to carry the fixture, and an insulator interposed between said supporting member and the bore of said block.

ARTHUR A. SCHWARTZ.
WILLIAM A. WHITESIDE.
